UNITED STATES PATENT OFFICE

WILBUR G. LAIRD, OF NEW YORK, N. Y., ASSIGNEE, BY MESNE ASSIGNMENTS, TO HEAT TREATING COMPANY, OF NEW YORK, N. Y., A CORPORATION OF DELAWARE

APPARATUS FOR AND METHOD OF DISTILLATION

Application filed December 24, 1924. Serial No. 757,788.

The present invention relates to the art of obtaining commercial products from raw liquids.

In my prior application, Serial No. 368,732, filed March 25, 1920, for process for the treatment of liquids with heat, I have described a method of treating materials to be distilled according to which oil or other liquid mixed with gas is fed forward through a plurality 10 of chambers or heat interchangers to a hot zone and vapors and hot residuum from said zone are passed back through said chambers countercurrent to the feed, the residuum, vapors and feed being separated by heat 15 transferring diaphragms. Also, my said application discloses transferring liquid condensed from the vapor stream in one of the heat interchangers into the feed flowing toward the heater zone. According to my said 20 application, the oil may be cracked or not, as desired.

A study of the operating records of my said invention has shown that the cases of relatively low efficiency have been those in which 25 relatively a small amount of vaporizable matter has been carried in the feed current in the heat interchangers through which the material passes to the hot zone, as compared to the amount of material which it is desired to 30 dense in said interchangers and contained in the vapor stream coming from said zone. Moreover, when operating on low volatile stock according to my said invention, the heat 35 efficiency has been materially improved by the transfer of condensate from the outgoing material into the ingoing material, as mentioned above. The condition of low fuel efficiency, due to low volatile content of the feed, practically always exists in cracking 40 processes as practised prior to my invention. Consequently, the present invention, in its specific aspect, relates more particularly to oil cracking operations.

The present application is a continuation 45 in part of my said application Serial No. 368,732 filed March 25, 1920, now Patent No. 1,546,345.

The principal object of the present invention is to assure a high fuel efficiency in the 50 heat treatment of liquids having relatively

low volatile content at the end boiling temperature of the product desired.

In carrying out the present invention, the feed stream, consisting of both liquid and a fluid, either vapor or gas, is passed forward 55 through heat interchangers to a hot zone and in counter-current relation to the vapor stream coming from said zone, the counter-current streams being separated by metal diaphragms. The liquid part of the feed is 60 made up from low volatile stock to which is added prior to introduction of the feed into the first heat interchanger a material which will volatilize at the end boiling point temperature of the desired product and under the 65 conditions maintained in the heat interchange apparatus. By suitably proportioning the stock and added material in the feed the heat required for volatilization on one side of the diaphragm or diaphragms absorbs 70 practically all the heat released by condensation on the other side of the diaphragm or diaphragms of material not desired in the final product. Since the material added to the feed will be volatile in the presence of gas 75 at the temperature existing in the first interchanger and the material passing from the last or coolest zone in the interchange circuit will be substantially a commercially pure product a minimum amount of heat need be 80 wasted in the condenser. Also the heat absorbed by the feed in the counter-current portion of the apparatus is carried forward to the heated zone so that there is substantially no 85 loss of heat due to condensing the undesired portion of the vapor stream coming from the hot zone.

It is known to crack oil in apparatus including both a still and a dephlegmator arranged to return liquid separated from the 90 outgoing vapors to the main body of oil being cracked. I have determined that better efficiencies are obtained in cracking processes if the reflux from the dephlegmator is not returned to the main body of oil being cracked except after such an intervening heat treatment as shall materially alter at least its physical characteristics and perhaps in large measure also its chemical characteristics.

A second object of the present invention is 100

to provide a process and apparatus, preferably of the so called tank and tube type or in other words one using a reaction chamber and a tube or pipe still for heating the oil to cracking temperature, which shall obtain the advantage of handling the reflux from the dephlegmator in the manner just mentioned.

A third object of the invention is to improve the operation of the tank and tube process and apparatus by introducing into the tube or pipe still with the oil to be cracked a fluid, either liquid or aeroform, which shall protect the gasoline that may form in the still from decomposition and facilitate the rapid escape of gasoline vapors from the still to the reaction chamber and from the chamber to the dephlegmator.

The novel features of the present invention are pointed out with particularity in the appended claims. The invention itself, however, with further objects and advantages, will best be understood from the following description taken with the accompanying drawings, in which

Fig. 1 is a diagrammatic view in elevation of an apparatus according to the present invention, and adapted to operate according to the process of the present invention, Fig. 1 being partly in section.

Fig. 2 is a vertical section through the heat interchange portion of the apparatus illustrated in Fig. 1.

Fig. 3 is a section on a line 3—3 of Fig. 2, looking in the direction of the arrows.

In the drawings, 6 is a pipe through which raw liquid material or stock to be operated on may be introduced into the system. In case the apparatus is to be operated according to a continuous process, a constant stream will be fed in through pipe 6. Liquid from pipe 6 passes into a receiver or tank 8, from which it is taken out by a feed pump 10 and forced up through pipe 12 to the first of the heat interchange and scrubbing trays or chambers 14 to 26 inclusive. The volatility in the presence of gas of the liquid introduced into the system through pipe 6 is modified as desired, according to the present invention. This may be done conveniently by liquid introduced into the tank 8 through pipe 28, the two streams of liquid from pipes 6 and 28 being thoroughly mingled in elements 8, 10 and 12 before reaching the heat interchanger 14.

Four streams of material pass through the heat interchangers 14 to 26 inclusive, such streams being separated by suitable metal partitions or conduits. The course of the incoming feed through chambers 14—26 is indicated diagrammatically in Fig. 1 by series of inclined dotted lines, 14a—26a inclusive. This feed includes not only the mixture of liquids mentioned above, but also a gas which is introduced into pipe 12 in a manner hereinafter mentioned. As appears clearly in

Fig. 1, the feed passes from the inlet end of pipe 12 through the chamber 14, and is conveyed from chamber 14 to chamber 16 by a connecting pipe 30. Identical pipes 30 connect the chamber 16—26 in series, as is clearly indicated on the drawings. Feed which has passed through the series of chambers or interchangers 14—26, as indicated by the inclined dotted lines 14a—26a, (Fig. 1) leaves chamber 26 by means of pipe 32. Pipe 32 conducts the feed to a heating coil 34 in furnace chamber 36. In coil 34 the material is heated to cracking temperature, and then discharged through pipe 38 into a cracking chamber 40. The major portion of the cracking occurs in the chamber 40, owing to the time required for the reaction to be completed. Vapors from the chamber 40 pass out through dome 42 and pipe 44, and these pass up through chambers 26—14, counter-current to the incoming feed. The path of the vapors through chambers 26—14 is indicated diagrammatically in Fig. 1 by the wavy dotted lines 26b—14b. The vapors are conducted from one chamber of the series 14—26 to the next through identical connecting pipes 46, 46. From the top chamber 14 vapors pass off through pipe 48 to condenser 50. The cooling effect of the ingoing feed condenses certain materials in the chambers 14—26, and these condensates may be taken off to the extent desired, to serve as finished products. Condensates from chamber 14 may be run off through pipe 52 and trap 54 and pipe 56 to condenser 50, and there mingled with the condensate formed from vapors passing into the condenser, or they may be drawn off through pipe 58, suitable valves in pipes 56 and 58 permitting this condensate to be discharged where desired. When so desired, condensates may also be taken off from chambers 16 and 18 through trapped pipes 60 and 62, respectively.

Gases not condensed in condenser 50 are drawn off through pipe 64 by gas pump 66 and forced into the feed line 12 through pipe 68. Superfluous gas may be withdrawn from the system through an outlet 70 connected to pipe 64. In starting up the apparatus, it is preferred to fill the system with gas through pipe 70, rather than wait for the desired amount of gas to build up during the operation.

Condensates formed in the trays 14—26 and not drawn off as product, flow back from one heat interchanger of the series to the next through a series of connecting pipes 72, 72 and are taken out from the bottom of the lowest chamber 26 through pipe 74. For practical reasons it is preferred to derive the liquid for modifying the feed, and previously described as introduced into the raw liquid feed line from pipe 28, from the condensate or reflux flowing out through pipe 74. Preferably this reflux is turned back through pipe

76 into chamber 26, this reflux then passing up through the chambers 26—14, its path through each of these chambers being indicated by broken horizontal lines 26c—14c respectively. The stream of reflux which is passed up through chambers 26—14 is led from one chamber of the series to the next through a set of identical connecting pipes 78, 78. In continuous operation, reflux passes out of top chamber 14 through pipe 80, which leads into pipe 28 previously mentioned. I do not limit myself, however, to passing the reflux back through trays 26—14, but may lead this reflux through valved pipe 77 directly into pipe 80, for purposes hereinafter described. As much as circumstances require of the reflux in pipe 80 may be passed through a cooler 82 on its way to pipe 28 and tank 8, suitable valves being provided to permit the reflux 20 to pass through or by pass the cooler.

The stream of reflux passing up through chambers 26—14 delivers a large proportion of the heat contained therein to the incoming feed. The main object, however, of utilizing the reflux is to provide volatilizable material in the feed stream, as previously mentioned. I do not limit myself to the use of reflux from heat interchangers or like column chamber or tray apparatus for mixing with the ingoing feed, but this material is convenient and suitable for the purpose when operating in accordance with the present invention. As the reflux material under consideration is taken in a liquid condition from the lowermost and therefore the hottest one of the chambers or trays 14—26, it may seem improbable that this material, when fed along with other material into the uppermost and therefore the coolest one of these trays 40 would volatilize sufficiently to give cooling effect in the uppermost tray. It has been demonstrated, however, that this is the case, and I attribute this effect to the action of the gas which forms a part of the incoming feed, as previously described. The incoming liquid, being heated in the trays 14—26 in the presence of a gas which has been stripped in condenser 50 of material volatile at the temperatures in the trays or chambers, 50 evaporates into the gas in much the same degree as might be the case if the feed were exposed to a vacuum at the temperatures within trays 14—26. This effect is well known in other circumstances, and is referred 55 to as the development of partial pressures.

One of the heat losses common in distillation processes is that caused by the rejection of hot residuum. In my prior application, Serial No. 368,732 above referred to, I have 60 disclosed a method of transferring the heat of the residuum mostly to the incoming feed by passing a stream of residuum countercurrent to the feed. I utilize this same principle in the apparatus when operating according to the present invention, by withdrawing

a certain amount of residuum from chamber 40 through pipe 84, having trap 86 therein. The residuum is delivered by pipe 84 into the lowermost chamber 26, and passes through the successive chambers 26—14 in 76 the same direction and parallel to reflux circuit 26c—14c previously described. The coils for the residuum, however, are not indicated on Fig. 1, but are illustrated in Figs. 2 and 3, and will be described in connection with the two latter figures. Preferably the residuum is not mixed with the reflux in chambers 26—14, but continues through chambers 26—14 in an entirely distinct circuit from any other fluid in said chambers. However, I do not limit myself to keeping the streams of residuum and reflux separate. When kept separate the residuum passes out of the upper chamber 14 through pipe 88, and may be conducted to storage or otherwise treated as desired. Residuum may also be drawn off of cracking chamber 40 through pipe 90, connected to pipe 84 adjacent to trap 86, whenever the temperature conditions in trays 14—26 render it desirable to 80 do so.

In order to prevent gases and vapors delivered to the still 40 through pipe 38 from passing directly to a vapor dome 42 and outlet pipe 44, or in other words short circuiting the cracking or reaction chamber, I prefer to place within tank or cracking chamber 40 an internal hollow cylinder 92, indicated in Fig. 1 by dotted lines. At one end cylinder 92 is formed with an elbow or 90° bend 94, the open end of which is directed downwardly above the delivery end of pipe 38. Material delivered to cracking chamber 40 through pipe 38, therefore, is projected at considerable velocity into the end of the cylinder 92, near the outlet 42, and passes thence through cylinder 92 to the end of tank 40 opposite outlet 42, whereby shortcircuiting of gases and vapor from pipe 38 to pipe 44 is effectually prevented, cylinder 92 also enables the vapors and gases to separate cleanly from the heavier material which collects in chamber 40. Moreover, the gas in the system is thus enabled to effectively scrub the residuum in chamber 40 of all light material and carry the same to the condenser. Tank 40 is preferably provided with a draw off 96 through which carbon or other undesired material may be discharged from the cracking zone when desired. 100

The interchangers 14—26 are shown in detail in Figs. 2 and 3.

The chambers 14—26 are all alike, but are arranged alternately right and left, in order to facilitate the flow of materials therethrough. Within each chamber 14—26 is a pair of internal diaphragms 98 and 100 respectively. The downwardly flowing stream of liquid feed and gas is introduced into the bottom of the space 102 between these two 115

diaphragms by feed pipe 12, previously mentioned. The pipe 12 is extended along the bottom of the space 102, and is perforated as indicated at 104 to permit a wide dispersion 5 of the incoming feed and gas into liquids collected in chamber 102. The feed and gas passes out of space 102 in chamber 14 through a pipe 30, previously mentioned, which passes through the diaphragm 98 near the upper 10 edge of this diaphragm and leads to the lower portion of space 102 in the next lower chamber of the series 14—26. In this way, the incoming liquid is repeatedly heated in the presence of gas by the bodies of liquid collected in spaces 102, these bodies of liquid 15 being kept hot and at substantially constant temperatures by upwardly flowing streams of vapors, reflux, and residuum.

The stream of vapors passing upwardly 20 from dome 42 through pipe 44 enters a space 106 formed in chamber or tray 26 between the diaphragm 98 and one end wall of the chamber. Pipe 44 is turned downwardly within the space 106, delivering the gases 25 near the bottom of this space through a rosette or the like 108. A body of condensate is maintained in each of the spaces 106 by overflow pipes 72 and the trap in the pipe 74 so that the vapors entering through the rosette, must bubble through this liquid thus 30 facilitating the condensation in chambers 106 of the heavier portions of the vapors. From space 106, of chamber 26 the vapors pass through space 102 by means of a nest of tubes 35 110 and are delivered to a space 112, formed at the opposite end of tray 26 between diaphragm 100 and the other end wall of the tray or chamber. From space 112 vapors pass upwardly through the succeeding trays 40 by means of pipes 46, 46 previously mentioned. Surplus reflux condensed in spaces 106 and tubes 110 of trays 16—24 is carried out from spaces 106 of upper trays to the spaces 112 of lower trays by means of pipes 45 72, 72 previously mentioned. The condensate in passing from spaces 112 to spaces 106 flows through the bottom tubes 110. The vapors introduced through the pipes 46 remove the lighter constituents and heavier 50 constituents flow downwardly through the chambers. Reflux passing out of the lowermost space 106 is delivered by pipe 76, previously mentioned, to a small header in space 102 of chamber 26, which is connected by 55 means of three or more pipes 114 to a similar header 116 Fig. 3, in space 102 of this chamber. From header 116 the reflux passes upwardly through pipe 78 previously mentioned to header 116 in space 102 of the next 60 higher chamber of the series 26—14, and so to pipe 80 previously mentioned.

The arrangement for carrying the residuum from pipe 84 through the trays 26—14 is similar to that for the reflux, and comprises a header 118 in the space 102 of tray 26, header

118, being connected to another header 118 within this space by three or more pipes 120. From the second header 118 the reflux passes up by connecting pipes 122, 122 and through similar headers and pipes 118—120 in the 70 spaces 102 of the remaining trays of the series 26—14 until it issues through the pipe 88 previously mentioned.

The operation of the apparatus according to the present invention and according to the present method will be obvious from the foregoing description. For purposes of convenience, however, the operation will be restated as follows: Stock is fed into the system continuously through pipe 6 and mixed with a 80 more volatile liquid and then with gas before being introduced into the first of a series of heat interchangers 14—26 through which the feed passes on its way to a heating coil 34. In heating coil 34, the feed liquid is brought 85 to the temperature desired, and usually to cracking temperature. From coil 34, the liquid and gas discharge into chamber 40 wherein vapors and gas separate from residuum. Vapor and gas are then passed through the 90 heat interchangers countercurrent to the ingoing feed. After leaving the heat interchangers, the gas is stripped of its vapors in condenser 50 and returned to the ingoing feed line. Reflux or condensate formed in heat interchangers 14—26 by partial condensation of vapors therein is preferably drawn from interchanger 26 and returned through all the interchangers counter-current to the feed. 95 Also residuum from chamber 40 is forced 100 through interchangers 14—26 counter-current to the feed whenever desired, before being discharged from the system. The streams of ingoing feed and outgoing vapor 105 are kept separate from all other materials within the heat interchangers by suitable means and the outgoing streams of reflux and residuum are also preferably kept separated from each other while in the heat interchangers. 110

It will be seen that the heat interchanging system comprising the chamber 26—14 and the parts associated therewith acts as a concentration unit superimposed on a cracking unit and operating entirely by what would otherwise be waste heat. The concentrating operation requires considerable amounts of heat and therefore affords opportunity for using the heat of the residuum as well as that of the vapors heavier than the product recovered from the condenser. A remarkably favorable heat balance is therefore obtained when working with the apparatus of and according to the process of the present invention. 115

It will be seen also that the process and apparatus according to the present invention involves the use of a complete circuit running through the still and condensers for a fluid 120 in addition to the feed, said fluid being prefer- 125

ably lighter than the product to be recovered and being specifically disclosed herein as a gas. However, the present invention is not limited to the use of a gas in this connection.

When operating to crack oil such as gas oil or heavier according to the present invention the feed stream composed of the initial feed of gas oil or other relatively heavy oil, the light fluid, reflux, and residuum contains practically the entire range of hydro-carbons except the gasoline fraction. The formation of gasoline in the heating coil or still 34 and in reaction chamber 40 is therefore promoted by the absence of an initial partial pressure in the gasoline range and a maximum yield is obtained because the gasoline vapors formed are quickly swept out of the coil 34, and the chamber 40, and are absorbed by other hydro-carbon gases and protected from decomposition. Particular attention is called to the fact that the reflux material added to the feed stream is material that has been vaporized in the still and cracking chamber 25 and that it is readily vaporized in coil 34. Its action throughout the process is materially different from that which would be the case if it were returned to chamber 40 in a liquid condition.

The preceding description is based on a continuous method of operation, the liquid feed being introduced in a steady stream through pipe 6. The same apparatus may, however, be operated on the batch principle. If it is desired to do this, a sufficient amount of liquid is introduced at one time, either through pipe 6, or otherwise, and the apparatus brought to the proper temperature and pressure, if pressure is used. When operating on the batch principle, however, it is necessary to maintain the thermal conditions within chambers 14-26 by substituting another source of fluid for that introduced through pipe 6 in the continuous method of operation. For this purpose I mix the reflux with the residuum, this may be done either by a pipe 124, connecting the pipe 88 with pipe 80, or by a pipe 85 connecting pipe 84 with pipe 80. Valves 126 and 128 in pipes 124 and 85 respectively permit the residuum to be discharged into the reflux pipe 80 when desired. A sufficient volume of liquid may thus be introduced into the tray 14 through pipe 12 to simulate the conditions obtained during continuous operation. The feed under these conditions, of course, is merely a mixture of reflux and residuum, and the composition of the liquids in the trays will not remain constant while running off a given batch. Nevertheless, I find that I can obtain high fuel efficiency with the apparatus herein disclosed when operated in accordance with the present invention on the batch principle.

It will be seen from the foregoing that the present invention utilizes the heat of the fuel

to maximum extent, the various individual losses having been reduced to a minimum.

Many features of the tray or chamber construction disclosed herein are illustrated in my prior application, No. 646,718, filed June 20, 1923, for process and apparatus for distillation, and are not claimed herein. Also the broad invention of evaporating material in a heat interchanger under conditions of agitation produced by a feed current containing gas is disclosed in my prior application, Ser. No. 349,262, filed January 3, 1920, and is not claimed herein.

Having thus described my invention, I claim:

1. A method of treating liquids comprising advancing liquid to a hot zone in heat interchanging relation to but out of contact with vapors passing from said zone, condensing a higher boiling point portion of the said vapors and passing said condensate into heat interchanging relation to but out of contact with said vapors and liquid, said condensate flowing in a direction countercurrent to said liquid and adding said condensate to said liquid prior to the point at which the liquid enters into heat interchanging relation to said vapors.

2. A method of treating liquids comprising continuously advancing liquid to a hot zone in heat interchanging relation to but out of contact with vapors passing from said zone, introducing gas into said liquid and passing the gas in contact with the liquid to the hot zone, withdrawing the gas with the vapors leaving the hot zone, condensing higher boiling point portions of the vapors and passing said condensate in heat interchanging relation to but out of contact with said vapors and liquid, adding said condensate to said liquid prior to the point at which the liquid enters into heat interchanging relation to said vapors and separating the gas from the remaining vapors by a condensation and returning the gas to the liquid.

3. A method of treating liquid comprising continuously advancing a liquid to a hot zone in heat interchanging relation to but out of contact with vapors passing from said zone, condensing higher boiling point portions of the said vapors and passing said condensate in heat interchanging relation to but out of contact with said vapors and liquid, said condensate flowing in a direction countercurrent to said liquid, adding said condensate to said liquid prior to the point at which liquid enters into heat interchanging relation to said vapors, removing residuum from the hot zone and circulating it in heat interchanging relation to but out of contact with said vapors and liquid, said residuum flowing in a direction counter-current to said liquid and removing the residuum from the system at the end of the countercurrent flow.

4. A method of treating liquids comprising

- continuously advancing liquid to a hot zone in heat interchanging relation to but out of contact with vapors passing from said zone, introducing gas into said liquid and passing the gas in contact with the liquid to the hot zone, withdrawing the gas with the vapors leaving the hot zone, condensing higher boiling point portions of said vapors and passing said condensate in heat interchanging relation to, but out of contact with said vapors and liquid, said condensate flowing in a direction counter-current to said liquid, adding said condensate to the said liquid prior to the point at which the liquid enters into heat interchanging relation to said vapors, separating the gas from the remaining vapors by condensation and returning it to the liquid, removing residuum from the hot zone and circulating it in heat interchanging relation to but out of contact with said vapors and liquid, said residuum flowing in a direction counter-current to said liquid, and removing the residuum from the system at the end of the counter-current flow.
5. In an apparatus for treating liquids, the combination of a reaction chamber, a dephlegmator receiving gases and vapors from said chamber, means for passing feed liquid through said dephlegmator counter-current to said gases and vapors, and means for passing reflux formed in the dephlegmator counter-current and in contact with said vapors to the hotter end of said dephlegmator and then through the dephlegmator in the same direction as said gases and vapors, but separate from both the vapors and the feed.
6. A combined dephlegmating and fractionating apparatus comprising a plurality of units each of said units having two internal partitions, tubes connecting the spaces in each unit on the outsides of said partitions, means for leading vapors and gases through said tubes of each of said units in series, means whereby liquid containing vaporizable material is passed in external contact with said tubes of each of said units in series and counter-current to the direction of flow of said vapors through the apparatus, means whereby liquid condensed from said vapors is maintained in each unit above the level of the incoming vapors and gases, and means for leading condensed liquid from one unit to the next in the direction opposite to the flow of vapors and gases.
7. A combined dephlegmating and fractionating apparatus comprising a plurality of units, each of said units having two internal partitions, tubes connecting the spaces in each unit on the outsides of said partitions, means for leading vapors and gases through said tubes of each of said units in series, means whereby liquid containing vaporizable material is passed in external contact with said tubes of each of said units in series and counter-current to the direction of flow of said vapors through the apparatus, means whereby liquid condensed from said vapors

said vapors through the apparatus, means whereby liquid condensed from said vapors is maintained in each unit above the level of the incoming vapors and gases, and means for passing said condensed liquid through the spaces in said units intermediate said partitions in the same direction from unit to unit as said vapors and in diaphragm contact with other liquids therein.

8. A combined dephlegmating and fractionating apparatus comprising a plurality of units, each of said units having two internal partitions, tubes connecting the space in each unit on the outsides of said partitions, means for leading vapors and gases through said tubes of each of said units in series, means whereby liquid containing vaporizable material is passed in external contact with said tubes of each of said units in series and countercurrent to the direction of flow of said vapors through the apparatus, means whereby liquid condensed from said vapors is maintained in each unit above the level of the incoming vapors and gases, means for running hot liquid from the same source as said vapors through the spaces in said units intermediate said partitions and in diaphragm contact with other liquids therein.

9. A combined dephlegmating and fractionating apparatus comprising a plurality of units having two internal partitions, tubes connecting the space in each unit on the outsides of said partitions, means for leading vapors and gases through said tubes of each of said units in series, means whereby liquid containing vaporizable material is passed in external contact with said tubes of each of said units in series and countercurrent to the direction of flow of said vapors through the apparatus, means whereby liquid condensed from said vapors is maintained in each unit above the level of the incoming vapors and gases, means for passing said condensed liquid through the spaces in said units intermediate said partitions in the same direction from unit to unit as said vapors and in diaphragm contact with other liquids therein, and means for running hot liquid from the same source as said vapors through the spaces in said units intermediate said partitions and in diaphragm contact with other liquids therein.

10. A combined dephlegmating and fractionating apparatus comprising a plurality of units, each of said units having two internal partitions, tubes connecting the space in each unit on the outsides of said partitions, means for leading vapors and gases through said tubes of each of said units in series, means whereby liquid containing vaporizable material is passed in external contact with said tubes of each of said units in series and countercurrent to the direction of flow of said vapors through the apparatus, means whereby liquid condensed from said vapors

is maintained in each unit above the level of the incoming vapors and gases, means for passing said condensed liquid through the spaces in said units intermediate said partitions in the same direction from unit to unit as said vapors and in diaphragm contact with other liquids therein, means for running hot liquid from the same source as said vapors through the spaces in said units intermediate 5 said partitions and in diaphragm contact with other liquids therein, and means for feeding fixed gas through the partitions in said units along with said liquid containing vaporizable material and for returning the 10 fixed gas through said units along with said vapors.

11. In an apparatus for treating liquids, the combination of a reaction chamber, a dephlegmator receiving gases and vapors 20 from said chamber, means for passing feed liquid through said dephlegmator counter-current to said gases and vapors, means for passing reflux formed in the dephlegmator counter-current and in contact with said vapors to the hotter end of the dephlegmator and then through the dephlegmator in the same direction as said gases and vapors, but separate from both the vapors and the feed, and means for putting some of said reflux 25 into said feed liquid prior to the entrance of the feed liquid into said dephlegmator.

12. An apparatus for distilling liquids, which comprises means for heating liquid to produce distillation thereof, a dephlegmator 35 means for passing liquid to be heated through said dephlegmator as a series of connected bodies, means for conducting liquid from the last of said bodies to said heating means, means for passing vapors from said heating 40 means through said dephlegmator counter-current to and in heat exchange relation with said liquid bodies but out of contact therewith thereby to produce partial condensation of said vapors, means for holding a portion 45 of the condensate produced by said heat exchange in heat transfer but out of contact with said liquid bodies, means for bubbling said vapors through said bodies of condensate, and means for passing gas into and for 50 bubbling it through the liquid in said series of connected bodies.

13. The process of cracking oils, which comprises cracking oil in a cracking zone to produce vapors therefrom, passing the vapors through a dephlegmating and rectifying zone where the higher boiling portion of said vapors is condensed, passing the condensate produced in said dephlegmating zone counter current to and in contact with said vapors, passing raw charging oil to be cracked through said dephlegmating zone in a confined circuit in heat exchange with said vapors and said condensate and mixing said condensate with said raw charging stock 55 prior to passing said stock through said

dephlegmating zone thereby to increase the heat transfer in said heat exchange.

14. The process of distilling oil, which comprises passing the oil to be distilled through a dephlegmating zone counter current to oil vapors from a distilling zone, passing reflux condensate formed in said dephlegmating zone counter current to and in contact with said vapors to the hotter portion of said dephlegmating zone and then through 70 said dephlegmating zone in the same direction as said vapors, but maintained out of contact therewith.

15. The method of treating liquids containing a relatively low percentage of volatile, which comprises mixing a raw low volatile liquid with another liquid of more volatile character, passing the resulting mixture so formed in heat transferring relation to, but separated from, a stream of vapors issuing 80 from a heating zone, thereby vaporizing some of said mixture, passing the said mixture together with the vapors formed therefrom into the heating zone from which said stream of vapors issues, and separating from 85 the vapors issuing from said zone by condensation, constituents comprising portions of said more volatile liquid for mixing with further quantities of the raw low volatile liquid to be treated.

16. A continuous process for distilling a liquid containing a relatively small percentage of light volatile constituents which comprises mixing with said liquid a second liquid of more volatile character and a gas, passing 100 the mixture through a series of heating zones of increasing temperature in indirect heat exchange with vapors passing in the opposite direction therethrough, thereby to vaporize portions of the liquid in said mixture and increase the relative amount of heat transferred from said vapors, maintaining the gas, vapor and liquid of said mixture in intimate contact with each other in said zones, further heating the mixture and introducing it into 105 a vapor separating zone, and conducting the vapors from said zone through said heating zones to supply hot vapors for heating said mixture.

17. The process of cracking oils, which comprises cracking oil in a cracking zone to produce vapors therefrom, passing the vapors through a dephlegmating and rectifying zone where the higher boiling portion of said vapors is condensed, passing the condensate produced in said dephlegmating zone counter current to and in contact with said vapors, passing raw charging oil to be cracked through said dephlegmating zone in a confined circuit in indirect heat exchange 120 with said vapors, maintaining a pressure on the charging oil substantially equal to that maintained in the rectifying zone and mixing said condensate with said raw charging stock 125 prior to passing said stock through said 130

dephlegmating zone thereby to increase the heat transfer in said heat exchange.

18. The process of cracking relatively heavy hydrocarbon oils, which comprises
- 5 passing the oil to be cracked through a series of heat exchange zones of increasing temperature in which the oil is heated by indirect heat exchange with hot cracked vapors, maintaining certain of said zones at a
  - 10 temperature sufficient to vaporize portions of said oil, passing vaporized and unvaporized portions of said oil from each zone in intimate contact with each other in each succeeding zone, passing the oil and vapors from the
  - 15 highest temperature zone of the series together in a confined stream through an additional high temperature heating zone in which the mixture is subjected to a cracking temperature, discharging the oil from said
  - 20 high temperature heating zone into intimate contact with a body of oil maintained in a vapor separating zone, maintaining such body of oil at a cracking temperature, and passing vapor separating therefrom through
  - 25 said heat exchange zones counter current to and in indirect heat exchange with the oil passing therethrough and in contact with bodies of condensate produced from said vapors.

30 In testimony whereof I affix my signature.
WILBUR G. LAIRD.
